ROTARY SWING

Jerry Brewster, Senior, Gypsum, Colo.

Application September 13, 1938, Serial No. 229,767

1 Claim. (Cl. 272—33)

The invention relates to swings and more particularly to rotary swings.

The primary object of the invention is the provision of a swing of this character, wherein a series of seats are suspended from a rotator so that the swing can be occupied by a plurality of persons and when seated it is possible through mechanical means manually operated for the rotation of the swing thereby giving amusement and affording pleasure to participants in the use of the swing.

Another object of the invention is the provision of a swing of this character, wherein each or a number of occupants can actuate the same for the driving of said swing, being rotatable, and the driving through manual control being effected with minimum labor or effort on the part of an operator.

A further object of the invention is the provision of a swing of this character, which is comparatively simple in its construction, thoroughly reliable and efficient in operation, readily and easily actuated, strong, durable and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is an elevation of a swing constructed in accordance with the invention.

Figure 2 is a fragmentary vertical sectional view thereof.

Figure 3 is a sectional view taken on the line 3—3 of Figure 1 looking in the direction of the arrows.

Figure 4 is a sectional view taken on the line 4—4 of Figure 1 looking in the direction of the arrows.

Figure 5 is an elevation partly broken away of certain adjuncts of the swing.

Similar reference characters indicate corresponding parts throughout the several views in the drawings.

Referring to the drawings in detail, the swing in its entirety comprises a vertical post or perpendicular shaft constituting an upright 10 fitted with a base 11 suitably anchored or at rest upon a foundation. Turnable on this upright 10 close to the upper end thereof is a horizontally arranged cross head in the form of a bar 12, being strengthened or reinforced by brace rods 13,

these being fitted to a winged collar 14 and also to the bar 12, respectively, the fitting of the rods 13 to the bar 12 being at the outer ends of said bar.

Depending from the under side of the bar 12 and at opposite sides of the upright 10 are bearings 15 in which are journaled rocking shafts 16 carrying hangers 17 and 17', respectively, for suspended swinging seats 18, each built with a platform 19. The upright 10 has fixed thereto a ratchet gear 20 with which coat ratchet pawls or dogs 21, these being arranged opposite each other and are pivoted at 22 to cranks 23 fixed to the shafts 16. The pawls or dogs 21 coacting with the ratchet gear 20 on the rocking of the shafts 16 effect the rotation of the bar 12 in a single direction and thus rotation of the swing is had. The hangers 17 are fixed to the shafts 16 next thereto while the hangers 17' are loose upon the shafts 16 next thereto. On the innermost hanger of the pair 17' there is fixed a pivot bracket 24 for pivotal support of a lever 25 which has pivotal connection at 26 with a pair of spaced links 27, these being pivoted at 28 to bearings 29 on the platform 19. The pivotal connection 26 constitutes a foot treadle operated by the foot or feet of an occupant of the seat suspended by the hangers 17'.

Connected with and active upon one of the links 27 is a coiled spring 30 which is also connected with the platform 19 and this spring is a retractile spring. The lever 25 has slidably connected therewith a cross head sleeve 31 pivotally mounted in spaced crank arms 32 fixed to the shafts 16 next thereto.

Arranged inwardly with respect to the innermost hanger 17 of the other pair is a lever 33, being journaled in a bearing 34 beneath the platform 19 next thereto. This lever 33 is pivotally connected to a link 35 which is pivoted to a crank arm 36 on a pedal operated shaft 37 having the foot pedals 38.

The lever 33 slidably fits in a cross head sleeve 39 pivoted to a pair of spaced crank arms 40 suspended from the bar 12, being fixed thereto and having clearances 41 for the shafts 16 next thereto.

An occupant of one of the seats 18 can manually manipulate through treadle action the treadle 26 and in this manner the swing will be caused to rotate in one direction. Now another occupant in the other seat 18 can operate the pedals 38 manually causing the shaft 37 to be rocked and thus through such pedal action there will be effected the rotation of the swing. Addi-

50
55

tionally, the seats 18 can be oscillated concurrently with the rotation of the swing and driving power furnished by occupants of either of the seats 18 or both.

6. What is claimed is:

A rotary swing comprising a fixed vertically disposed stationary shaft, a horizontally arranged bar forming a cross head having a central sleeve-like hub rotatably fitting the upper end 10 of said shaft, bearings depending from the underside of said bar beyond opposite sides of the shaft, rocking shafts journaled in said bearings and extending laterally from opposite sides of the shaft, a ratchet gear fixed to the first mentioned shaft, cranks fixed to said second named shafts, ratchet dogs pivoted to said cranks and reversely operative with the said ratchet gear,

a pair of hangers fixed to one of the last mentioned shafts, a pair of hangers loosely fitted with the other of the said pair of last mentioned shafts, seats carried by said hangers, levers swingable relative to said seats, means associated 5 with the seats for imparting swinging movement to said levers and manually controlled, pairs of crank arms, one pair being fixed to one of the pair of last mentioned shafts, the other pair of crank arms being in loose embracing 10 engagement with the other of said pair of last mentioned shafts and suspended from the cross head bar, and cross head sleeves pivoted to the pairs of crank arms and slidably fitted with the swinging levers. 15
